(57) **CLAIM**

The ornamental design for a multipurpose keychain tool, as shown and described.

DESCRIPTION

FIG. 1 is a front-bottom-right isometric view of a multipurpose keychain tool according to our new design.

FIG. 2 is a front-top-left isometric view of the multipurpose keychain tool of FIG. 1.

FIG. 3 is a back-top-right isometric view of the multipurpose keychain tool of FIG. 1.

FIG. 4 is a back-bottom-left isometric view of the multipurpose keychain tool of FIG. 1.

FIG. 5 is a front view of the multipurpose keychain tool of FIG. 1.

FIG. 6 is a back view of the multipurpose keychain tool of FIG. 1.

FIG. 7 is a top view of the multipurpose keychain tool of FIG. 1.

FIG. 8 is a bottom view of the multipurpose keychain tool of FIG. 1.

FIG. 9 is a left side view of the multipurpose keychain tool of FIG. 1; and,

FIG. 10 is a right side view of the multipurpose keychain tool of FIG. 1.

1 Claim, 8 Drawing Sheets
